(57) **CLAIM**

The ornamental design for an overlapping rain garment as shown.

DESCRIPTION

FIG. 1 is a perspective view of an overlapping rain garment; FIG. 2 is front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof. The broken lines in the drawings depict portions of the garment that form no part of the claimed design.
